CLIP AND CAP FOR POCKET CARRIED IMPLEMENTS

Rose, R. Eratico, Long Island City, N. Y.

Application April 5, 1948; Serial No. 18,966

7 Claims. (Cl. 24—11)

1

This invention relates to a clip and cap for pocket carried implements.

An object of the present invention is to provide a clip, which may be readily and securely attached to a cap of a pocket carried implement without the use of machinery.

A further object of the present invention is to provide a cap for a pocket carried implement, which may be readily manufactured at low costs.

Another object of the present invention is to improve upon the construction of clips and caps for pocket carried implements as now ordinarily made.

With the above and other objects of the invention in view, the invention consists in the novel construction, arrangement and combination of various parts, as set forth in the claims hereof, a certain embodiment of the same being described in the specification and being illustrated in the accompanying drawings, forming part of this specification, wherein:

Fig. 1 is a side elevational view, partly in section, of a cap provided with a clip according to the invention,

Fig. 2 is a side elevational view similar to that shown in Fig. 1, wherein, however, the clip is shown in a position during its attachment to the cap;

Fig. 3 is a perspective rear view of the clip according to the invention, and

Fig. 4 is a front elevational view of the clip.

Referring to the drawings, 10 indicates a cap of a pocket carried implement, such as a fountain pen, mechanical pencil, flashlight or the like. Said cap 10 is provided with two slots or apertures 12, 14 spaced from each other at the distance *a* in the direction of the length of the cap.

16 generally indicates a clip made of an integral body of spring material. The body of said clip comprises an elongate shank 18 having a bulbous tip 20 or the like at one of its ends and having an offset end portion 22 at its other end. Said offset end portion 22 includes a portion 24 bent away from the shank 18, folded back upon itself at 26 toward and under said shank 18 and bent again away from said shank at 28. Thus, a bend is formed in said offset portion, said bend being disposed opposite the shank 18 and the apex of said bend being adjacent said shank.

The distance *b* between the fold 26 and the free end 30 of the offset end portion 22 is larger than the distance *a* between the slots 12 and 14 of the cap 10.

The clip 16 may be attached securely to the cap 10 in the following manner: As shown in Fig. 2,

2

the free end 30 of the offset end portion 22 of the shank 18 of the clip 16 is inserted into the slot 14 of the cap 10 and the clip is held by hand against the wall of the cap. Thereupon, the folded portion 26 of the offset end portion 22 is manually pushed downward and into the slot 12 against the action of the resilient bend anchored at this time with its free end 30 in the slot 14. Owing to the resiliency of the material of the clip 16, the folded portion 26 snaps readily into the slot 12, whereupon the clip assumes the position shown in Fig. 1. Now, the clip 16 is securely attached to the cap 10. The resilient bend tends to return to its original shape with a distance *b* between the fold 26 and the free end 30 larger than the distance *a* between the slots 12 and 14; in other words, the legs 26, 30 of the bend are spread apart, whereby said legs are tightly held in the slots 12 and 14 and the clip is securely attached to the cap 10. Furthermore, the portions folded upon each other at 26 have the tendency to spread apart, thus causing an additional clamping action in the slot 12.

The extreme simplicity of the clip is apparent from inspection; the clip can readily be attached to the cap by hand; the attachment of the clip to the cap is very secure; the clip and the cap may be manufactured at low costs.

What I claim is:

30. 1. A clip for a pocket carried implement comprising: an integral body including an elongate shank and an offset end portion, said offset end portion comprising a portion bent away from said shank, folded closely back upon itself toward and under said shank and bent again away from said shank.

2. A clip for a pocket carried implement comprising: an integral body of spring material including an elongate shank and an offset end portion, said offset end portion comprising a portion bent away from said shank, folded closely back upon itself toward and under said shank and bent again away from said shank.

3. In combination: a cap for a pocket carried implement, said cap having formed in the wall thereof two apertures spaced from each other in the direction of the length of the cap, and a clip having an integral body of spring material including an elongate shank, and an offset end portion, said offset end portion comprising a portion bent away from said shank, folded closely back upon itself toward and under said shank and bent again away from said shank, the folded portion and the free end of said offset end portion being inserted into said two apertures of said cap.

55

4. In combination: a cap for a pocket carried implement, said cap having formed in the wall thereof two apertures spaced from each other at a predetermined distance in the direction of the length of the cap, and a clip having an integral body of spring material including an elongate shank and an offset end portion, said offset end portion comprising a portion bent away from said shank, folded closely back upon itself toward and under said shank and bent again away from said shank, the folded portion and the free end of said offset end portion being inserted into said two apertures of said cap, and the distance between said folded portion and said free end of the offset end portion being larger than the distance between said apertures of the cap.

5. A clip for use in connection with a pocket borne implement having a longitudinal wall portion pierced by two apertures spaced from each other in the longitudinal direction, said clip comprising a substantially straight portion adapted to extend adjacent said wall portion and spaced therefrom and being bent near one end of said straight portion and thence folded and bent arcuately in an opposite direction adjoining for a portion said first bend to form therewith a folded portion and then increasingly being spaced from same and from said straight portion and having a terminal portion forming an angle with said folded portion, said terminal portion arranged to be inserted in one of said apertures and said folded portion in the other.

6. A clip for use in connection with a pocket borne implement having a longitudinal wall portion pierced by two apertures spaced from each other in the longitudinal direction, said clip including a preformed structure made of a single elongated resilient piece comprising a shank portion arranged to be disposed adjacent said wall portion and spaced therefrom, an arcuate portion at one end of said shank portion, a folded portion on said arcuate portion, and a second arcuate portion extending from said folded portion

5 and having its convex side facing towards said shank portion and including a terminal portion adapted to be inserted in one of said apertures and forming an angle with said folded portion, said folded portion having two parts sufficiently closely adjoining to be subsequently inserted together in the other aperture for resiliently removably securing said clip in said apertures.

10 7. A clip for use in connection with a pocket borne implement having a longitudinal wall portion pierced by two apertures spaced from each other in the longitudinal direction, said clip made of a single blank of resilient material having a certain thickness and comprising an end portion having lateral opposite extensions adapted to be folded towards one another to form a bulbous tip, an elongated portion adjacent thereto to form a shank and being bent transversely of its length for increasing lengthwise the rigidity of said shank, an extension on said shank being bent first longitudinally of said shank and thence folded sharply and bent arcuately back on said extension to form a fold of substantially twice said certain thickness and terminating at 15 an angle to said fold and spaced therefrom for a distance sufficiently to permit insertion and retaining of said fold in one aperture and said terminus in the other aperture, whereby, due to the resiliency and angle therebetween, said fold and terminus will be mounted removably on said wall portion.
